UNITED STATES PATENT OFFICE.

SANFORD A. MOSS, OF LYNN, MASSACHUSETTS, ASSIGNOR TO GENERAL ELECTRIC COMPANY, A CORPORATION OF NEW YORK.

GAS PRODUCER.

Application filed February 27, 1923. Serial No. 621,656.

To all whom it may concern:

Be it known that I, SANFORD A. Moss, a citizen of the United States, residing at Lynn, county of Essex, State of Massachusetts, have invented certain new and useful Improvements in Gas Producers, of which the following is a specification.

The present invention relates to gas producers of the type wherein the steam required for the gas producer process is used also as a pumping fluid for supplying the air required, the steam being utilized in a jet blower or ejector. In this process of gas manufacture, air and steam are required in certain definite proportions and considerable difficulty has been experienced in obtaining the correct mixture and at the same time producing sufficient pressure to force the air and steam through the bed of fuel. In fact, in the process as heretofore practiced, it had been necessary to use a comparatively thin bed of fuel in order that the steam and air would pass through it. It is, of course, desirable to use a comparatively thick fuel bed but with the systems in use, this was not possible because when sufficient steam was used to force the steam and air through a thicker fuel bed, the amount of steam used became entirely too great proportionately to the air pumped. As a result, it has been necessary to use comparatively thin fuel beds in gas producers of this character.

Now, according to my invention, I provide an ejector or jet blower having such proportions that with the thickest desired fuel bed, the quantity of steam required to produce the pressure necessary to force the steam and air through it will not be out of proportion to the quantity of air, and I then provide an auxiliary steam pipe for supplying any deficiency in the steam to bring the quantity of steam up to the desired amount.

Preferably I employ an ejector pump or jet blower of the general character illustrated and described in my Patent No. 1,264,116 patented April 23, 1918, wherein there is provided a plurality of nozzles for both the pumping fluid and the fluid to be pumped, said nozzles being interspersed among each other with their discharge ends lying in substantially the same plane and all designed to convert pressure into velocity.

In the drawing, Fig. 1 is a vertical sectional view of a gas producer equipped with an ejector or jet blower embodying

my invention; Fig. 2 is a vertical sectional view of the the ejector, and Fig. 3 is a top plan view of the steam nozzles, the casing being shown in section.

Referring to the drawing, 5 indicates a gas producer having a chamber 6 which holds the fuel charge 7, and a gas discharge conduit 8. Associated with chamber 6 is an ejector type pump or jet blower having a plurality of steam nozzles 9 carried by a frame 10 and supplied with steam by a conduit 11. The throats of nozzles 9 are indicated at 9^a. Surrounding steam nozzles 9 is a casing 12, the upper end of which forms a discharge tube, which is first converging and then diverging, the throat being indicated at 13. The discharge ends of steam nozzles 9 terminate in the converging portion of the discharge tube. The lower end of casing 12 is open as is indicated at 12^a for the admission of air. The general arrangement illustrated and so far described is to be taken as typical of any suitable gas producer. The operation of such a gas producer is well understood.

According to my invention, I decrease the size of throat 13 to such an extent that its area A is less than one hundred times greater than the sum of all the areas in the throats 9^a of steam nozzles 9. Representing the sum of the areas of throats 9^a by the letter a, then the arrangement is such that $\frac{A}{a}$ is less than 100. Preferably, I utilize a value of $\frac{A}{a}$ equal to about 80. With this arrangement,

I am enabled to pump a desired amount of air with a comparatively small amount of steam and to effect flow of the steam and air through throat 13 at a high velocity. This steam and air passing through throat 13 enters the diverging portion of the discharge tube and there has its velocity converted into pressure, and by reason of my invention, the pressure created will be sufficient to force the mixture of steam and air through a fuel bed of the desired thickness. In the use of my invention there may be insufficient steam used in the ejector for carrying out the gas making process (this in contrast to excess steam of previously known apparatus) and to take care of this condition, I provide an auxiliary steam pipe 14 for supplying additional steam to the apparatus. Prefer-

ably, pipe 14 supplies the steam adjacent the active end of the discharge tube of the ejector.

By the use of my invention I am enabled in the blowing of gas producers to use thicker beds of fuel than heretofore and at the same time maintain always the correct proportions of air and steam.

In accordance with the provisions of the patent statutes, I have described the principle of operation of my invention, together with the apparatus which I now consider to represent the best embodiment thereof, but I desire to have it understood that the apparatus shown is only illustrative and that the invention may be carried out by other means.

What I claim as new and desire to secure by Letters Patent of the United States, is:

1. In a gas producer, in combination, a fuel chamber, air and steam admission means comprising a steam-actuated jet blower for blowing air and steam into the fuel charge, said jet blower having a discharge tube and steam nozzle means, and the area of the throat of the discharge tube being not more than one hundred times greater than the total steam nozzle throat area.

2. In a gas producer, in combination, a fuel chamber, air and steam admission means comprising a steam-actuated jet blower for blowing air and steam into the fuel charge, said jet blower having a discharge tube and steam nozzle means, and the area of the throat of the discharge tube being not more than one hundred times greater than the total steam nozzle throat area, and a conduit for supplying additional steam to the producer independently of said jet blower.

3. In a gas producer, in combination, a fuel chamber, air and steam admission means

comprising a steam-actuated jet blower for blowing air and steam into the fuel charge, said jet blower having a discharge tube which is first converging and then diverging, and the area of the throat of the discharge tube being not more than one hundred times greater than the total steam nozzle throat area.

4. In a gas producer, in combination, a fuel chamber, air and steam admission means comprising a steam-actuated jet blower for blowing air and steam into the fuel charge, said jet blower having a discharge tube and a plurality of steam nozzles, and the area of the throat of the discharge tube being not more than one hundred times greater than the total steam nozzle throat area.

5. A gas producer, in combination, a fuel chamber, air and steam admission means comprising a steam-actuated jet blower for blowing air and steam into the fuel charge, said jet blower having a discharge tube having a convergent portion which terminates in a throat and steam nozzle means which terminates in said convergent portion, the area of the throat being not more than one hundred times greater than the total steam nozzle throat area.

6. In a gas producer, in combination, a fuel chamber, air and steam admission means comprising a steam-actuated jet blower for blowing air and steam into the fuel charge, said jet blower having a discharge tube provided with a convergent portion which terminates in a throat and a plurality of steam nozzles which terminate in said convergent portion, the area of the throat of the discharge tube being not more than one hundred times greater than the total steam nozzle throat area.

In witness whereof, I have hereunto set my hand this 23rd day of February, 1923.

SANFORD A. MOSS.
